CASEMENT WINDOW

Donald Heaney, Essex Junction, Vt.

Application July 15, 1941, Serial No. 402,467

4 Claims. (Cl. 189—69)

This invention relates to hinged windows, doors, or other hinged closures, and pertains more particularly to improvements in the construction of windows having sashes pivoted to swing against a stationary jamb when the window is closed.

The principal purpose of the invention is to provide a hinged sash which, when latched in closed position against a jamb or frame, will snugly and resiliently engage the window jamb on all sides, thereby avoiding rattling and preventing objectionable drafts and water seepage which are characteristic of the ordinary casement windows and other hinged closures.

More specifically, it is an object of this invention to furnish a tight-fitting, but easily latching, casement window having sash members which are relatively resilient and normally bowed transversely with respect to the plane of the sash, as hereinafter explained, so that the latching of the closed window at a point near the center of its free side will cause all sides of the sash to be flattened snugly against the jamb.

A further object is to provide means for hinging the sash to a window frame in such a manner that the ends of the hinged side of the sash are yieldingly urged toward the jamb by springs contained in the frame mountings, which supplement the action of the latching devices in pressing the sash against the jamb.

A recommended embodiment of the invention is illustrated in the accompanying drawings, in which:

Fig. 1 is an inside elevation of a casement window which opens inwardly;

Fig. 2 is a view similar to Fig. 1, showing the window sash removed from its frame;

Figs. 3 to 6 are edge views of the metal sash members, illustrating with considerable exaggeration the manner in which said members are bowed in normal or opened position of the window; Fig. 3 showing the free side of the sash, Fig. 4 the top end, Fig. 5 the hinged side, and Fig. 6 the bottom end thereof;

Fig. 7 is an enlarged section on lines 7—7 of Fig. 1;

Fig. 8 is an enlarged and broken end view of the window frame, illustrating the hinge mounting for pivotally connecting the sash to the frame;

Fig. 9 is a section on line 9—9 of Fig. 8;

Fig. 10 is a detail perspective view of a hinged corner of the sash and frame, the window pane being omitted and a portion of one of the hinge members being broken away;

Fig. 11 is a detail, fragmentary perspective of the latching device; and

Fig. 12 is an enlarged detail of a sleeve member forming part of the hinge connection.

It will be appreciated that the drawings are merely illustrative of a suggested form of the improved window, and somewhat diagrammatic in character; and it will be understood that a hinged closure constructed in accordance with this invention may be fashioned in various sizes and shapes suitable for particular purposes, and that the structural details of the hinge members may be varied widely without departing from the essence of the invention as defined in the appended claims.

The window sash shown in the drawings is preferably made of light-weight steel or other metal having sufficient flexibility and resiliency to be given a curved or bowed shape and to yield resistantly under pressure, so that the bowed sash members may be flattened against the window jamb or frame when forcibly latched, but will resume their normal curvature when the sash is unlatched. It will be understood, however, that the sash may be made of wood, plastics or other suitable materials which will satisfy the purposes of this invention; and it will also be understood that the sash may form part of a door or other hinged closure, as well as of a casement window.

The window may be mounted to swing inwardly or outwardly with respect to the frame, but is here shown as opening inwardly or toward the observer in Figs. 1 and 2. The window frame may be of rigid metal, wood, or other suitable material, and has the usual flat jamb against which the bowed members of the sash are abutted and flattened when the window is closed and tightly latched. It will be apparent, however, that a bowed frame or jamb may be employed with a flat sash, to achieve the purposes of this invention.

The improved sash selected for the purpose of illustration comprises a free side member 13, a top end 14, a hinged side 15 and a bottom end 16; and may have one or more division bars 17 separating the glass panes 18, 19. The side 15 is equipped with hook-shaped pintles 20 located adjacent its opposite ends and received in slotted, spring-containing sleeves 21 mounted on the window frame 22, as hereinafter described. As shown, the sash members are L-shaped and the frame members are T-shaped in cross-section; but other shapes may obviously be selected.

The edges of the glass panes may be mounted

in cushioning strips 23 of felt, rubber or the like, and retained by metal moldings 24 screwed to the sash as shown in Fig. 7. The cushion strips not only make the panes weather-tight, but also absorb any harmful stresses which might be imparted to the glass by the intermittent flattening and bowing of the sash members, as the window is closed and reopened.

Each hinge pin 20 is fastened to the sash member 15 by rivets 25 (Fig. 9) and its depending end is formed with a round head or collar 26 providing an annular shoulder 27 (Fig. 10). The head 26 is freely received in the enlarged end 28 of the slot 29 in the wall of the tube or sleeve member 21, the latter having an integral extension 30 which is screwed or otherwise secured to the web of the T-shaped frame 22 (Fig. 12). After entering the opening 28, the pivot head slides inwardly of the sleeve 21 toward the end of slot 29, and is yieldingly held in that position—with the shoulder 27 engaged under the overhanging rims of the slotted sleeve—by a stout compression spring 31 bearing on a follower 32 and retained by a screw cap 33 threading on the outer end of the sleeve member and adapted to regulate the compression of the spring.

When the sash is closed, the springs 31 tend to urge and maintain the ends of sash member 15 flush against the jamb 34 of the window frame, as shown in Fig. 9, but the springs will yield while the sash is being closed so that the pintles 20 may move outwardly in the sleeves 21, thereby to permit all the sash members to be flattened by the clamping action of the latching device provided at the center of the free side 13.

The latch comprises a rotatable lever pivoted at 35 to a plate 36 riveted to the sash side 13 near its center (Fig. 11) and having a handle portion 37 and locking bar 38; and a catch or hook member 39 fastened to the web of the frame 22 and having an inclined surface 40 terminating in a flat face 41 against which the bar 38 bears when the latch is moved to locking position. It will be apparent that the cramping action of closing the latch causes the sash member 13 to be pressed inwardly at its center, toward and snugly against the jamb 34.

As best shown in Figs. 3 to 6, the sash members of the window are normally bowed transversely, the degree of curvature being substantially exaggerated in the drawings. In practice the curvature would be relatively slight and merely sufficient to allow the resilient sash members to be flattened against the jamb upon latching the window, in accordance with the objects of this invention. The sash member 13 at the free side of the window is bowed outwardly at its center with respect to the jamb; and the members 14, 15 and 16 are bowed inwardly at their centers.

Hence, when the window is moved toward closing position, the jamb is first engaged by the center of the hinged side 15, the springs 31 of the hinge members initially yielding as the sash is pressed inwardly; then the centers of the sash ends 14 and 16 meet the jamb; and finally the center of the side 13 is forced snugly against the jamb by wedging the latch bar 38 to seating position along the inclined edge 40 and under the flat face 41 of the catch 39. This action not only flattens the side 13 but also flattens the end members 14 and 16 and the hinged side 15, the ends of the latter sash members being urged inwardly by the springs 31. The entire periphery of the sash is thus firmly and tightly seated against the jamb of the window frame and held in snug en-

gagement by the distortion of the resilient sash members which resist any tendency to displacement until the latch is released.

A casement window constructed as herein described cannot rattle or chatter and is substantially weather-proof when latched; yet it may be easily opened and closed, and will swing freely on its hinge pintles. Any usual attachment (not shown) may be provided for holding the opened window in adjusted position, and it will be apparent that the improved sash may be applied to any ordinary window frame without appreciable alteration.

As previously indicated, a bowed sash of the character just described may be employed for a door, screen or other hinged closure shutting against a frame jamb; and the benefits of the bowed construction will be attained—partially if not completely—by hinging a flat sash to a jamb which is curved relative to the plane of the meeting surfaces, or by utilizing both a curved sash and a curved jamb, so long as the relative curvature of the meeting surfaces requires that the center of the hinged side of the sash, the centers of the opposite ends of the sash, the ends of the free side of the sash and then the center of said free side successively engage the jamb when the hinged sash is moved toward closing position.

It will also be understood that the term "jamb" as used herein is employed in its general sense and is intended to include the abutment surface of a side or center mullion, a head bar, a sill, or the meeting rail or stile of a companion sash, of a closure frame.

A hinged closure and sash constructed in accordance with this invention ensures a snug and tight fit between the meeting faces of the parts, without the necessity of providing special cross sectional shapes for said parts or special weather stripping to prevent rattling or moisture seepage.

I claim:

1. A hinged closure of the character described, comprising a frame having a jamb, a sash having side and end members closing against the jamb, and resilient means pivotally connecting the end portions of one of said side members to the frame, the sash members and jamb having meeting surfaces and the surfaces of each of the sash members being curved transversely of the plane of said meeting surfaces, the hinged side and the ends of the sash having their inner surfaces curved inwardly at their centers with respect to the jamb, and the free side of the sash having its inner surface curved outwardly at its center, so that when the sash is moved toward closing position the centers of its hinged side and its ends initially engage the jamb and the ends of its free side subsequently engage the jamb, and cooperative latching devices on the frame and on the central portion of said free sash side for forcing said central portion inwardly and securing it snugly against the jamb.

2. A casement window comprising a frame having a jamb, a sash having side and end members of relatively resilient material, means hingedly connecting one of the side members to the frame, said means comprising spring-pressed elements disposed near the respective ends of the hinged side member for pressing said ends toward the jamb when the window is closed, each of said members being normally bowed transversely with respect to the plane of the sash, the hinged side and the end members being bowed inwardly at their centers with respect to the jamb and the free side member being bowed outwardly at its

center, and cooperative latching devices on the frame and on the central portion of said free side member for forcing said portion inwardly and securing it against the jamb, whereby all of the sash members are flattened and snugly engage the jamb.

3. A casement window comprising a frame having a jamb, a sash having side and end members of relatively resilient metal, means hingedly connecting one of the side members to the frame, said means comprising pintles adjacent the respective ends of such side members and frame mountings having springs for pressing the pintles toward the jamb when the window is closed, each of said sash members being normally bowed transversely with respect to the plane of the sash, the hinged side and the end members being bowed inwardly at their centers with respect to the jamb and the free side member being bowed outwardly at its center, and cooperative latching devices on the frame and on the central portion of said free side member for forcing said portion inwardly and securing it against the jamb, whereby all of the sash members are flattened and snugly engage the jamb.

4. A casement window comprising a frame having a jamb and hinge mountings extending outwardly of the jamb, each of said mountings including a slotted sleeve for receiving a pintle of a sash, a spring adapted to press the pintle toward the jamb and a cap threading on the sleeve for adjusting the compression of the spring, a sash having side and end members of relatively resilient metal, one of the side members having pintles fastened adjacent its opposite ends and received in said slotted sleeves for longitudinal movement therein, each of said sash members being normally bowed transversely with respect to the plane of the sash, the hinged side and the end members being bowed inwardly at their centers with respect to the jamb and the free side member being bowed outwardly at its center, and cooperative latching devices on the frame and on the central portion of said free side member for forcing said portion inwardly and securing it against the jamb, whereby all of the sash members are flattened and snugly engage the jamb.

DONALD HEANEY.
